(57) **CLAIM**

The ornamental design for a sample vessel, as shown and described.

DESCRIPTION

FIG. 1 is a top front isometric view of a first embodiment of a sample vessel showing our new design, with the sample vessel top open;

FIG. 2 is a top left side isometric view thereof;

FIG. 3 is a bottom left side isometric view thereof;

FIG. 4 is a front elevational view thereof;

FIG. 5 is a rear elevational view thereof;

FIG. 6 is a cross-sectional view taken along line 6-6 of FIG. 4 thereof;

FIG. 7 is a right side elevational view thereof;

FIG. 8 is a left side elevational view thereof;

FIG. 9 is a cross-sectional view taken along line 9-9 of FIG. 7 thereof;

FIG. 10 is a top plan view thereof;

FIG. 11 is a bottom plan view thereof;

FIG. 12 is a top front isometric view of a second embodiment of a sample vessel showing our new design, with the sample vessel top closed;

FIG. 13 is a top left side isometric view thereof;

FIG. 14 is a bottom left side isometric view thereof;

FIG. 15 is a front elevational view thereof;

FIG. 16 is a rear elevational view thereof;

FIG. 17 is a cross-sectional view taken along line 17-17 of FIG. 15 thereof;

FIG. 18 is a right side elevational view thereof;

FIG. 19 is a left side elevational view thereof;

FIG. 20 is a cross-sectional view taken along line 20-20 of FIG. 18 thereof;

FIG. 21 is a top plan view thereof; and,

FIG. 22 is a bottom plan view thereof.

The portions of the sample vessel depicted in broken dash lines represent the bounds of the claim and form no part of the claimed design. As to the broken lines denoting the
